(57) CLAIM

We claim the ornamental design for a view saver umbrella, as shown and described.

DESCRIPTION

FIG. 1 is a top plan view of a view saver umbrella, shown in a folded state and showing our new design;

FIG. 2 is a bottom view of the view saver umbrella, shown in a folded state; and,

FIG. 3 is a top perspective view of the view saver umbrella, shown in an open state.

The broken lines depict portions of the view saver umbrella that form no part of the claimed design.
